UNITED STATES PATENT OFFICE

138,899

DESIGN FOR AN ALLIGATOR SHEAR OR
SIMILAR ARTICLE

Lad L. Hercik, Lakewood, Ohio, assignor to The
Hill Acme Company, Cleveland, Ohio, a cor-
poration of Ohio

Application January 26, 1944, Serial No. 112,334

Term of patent 14 years

(Cl. D54—14)

To all who it may concern:

Be it known that I, Lad L. Hercik, a citizen of the United States, residing in Lakewood, in the county of Cuyahoga and State of Ohio, have invented a new, original, and ornamental Design for Alligator Shears or Similar Articles, of which the following is a specification, reference being had to the accompanying drawings, forming part thereof.

Fig. 1 is a perspective view of an alligator shear embodying my new design and showing principally the right side of this shear.

Fig. 2 is a right side elevation of the alligator shear shown in Fig. 1.

Fig. 3 is a left side elevation thereof.

Fig. 4 is a front elevation thereof.

Fig. 5 is a plan view thereof.

I claim:

The ornamental design for an alligator shear or similar article, as shown.

LAD L. HERCIK.
